(57) **CLAIM**

The ornamental design for a trailer brake controller, as shown and described.

DESCRIPTION

FIG. 1 is a perspective view of a trailer brake controller, showing our new design.

FIG. 2 is a front elevation thereof;

FIG. 3 is a rear elevation thereof;

FIG. 4 is a first side elevation thereof;

FIG. 5 is a second side elevation thereof;

FIG. 6 is a top plan elevation view thereof; and,

FIG. 7 is a bottom plan view thereof.

The broken line portions of the figure drawings are included to show unclaimed subject matter only and form no part of the claimed design.

1 Claim, 4 Drawing Sheets
